(57) **CLAIM**

The ornamental design for an “ice scoop,” as shown and described.

DESCRIPTION

FIG. 1 is a top, front, and left side perspective view showing one example of our new design for an ice scoop.

FIG. 2 is a left side view of the ice scoop shown in FIG. 1, the right side view being a mirror image thereof.

FIG. 3 is a front view of the ice scoop shown in FIG. 1.

FIG. 4 is a rear view of the ice scoop shown in FIG. 1.

FIG. 5 is a top view of the ice scoop shown in FIG. 1

FIG. 6 is a bottom view of the ice scoop shown in FIG. 1.

FIG. 7 is a rear and left side perspective view of the ice scoop shown in FIG. 1.

FIG. 8 is a top, front, and left side perspective view showing an alternate transparent example of our new design for an ice scoop; and,

FIG. 9 is a rear and left side perspective view of the ice scoop shown in FIG. 8.
